G. W. CHRISTIANS.
METHOD OF SEALING CREEVICES IN ROCK FORMATIONS.
APPLICATION FILED JUNE 9, 1919.

1,327,268.

Patented Jan. 6, 1920.

UNITED STATES PATENT OFFICE.

GEORGE W. CHRISTIANS, OF CHATTANOOGA, TENNESSEE.

METHOD OF SEALING CREVICES IN ROCK FORMATIONS.

1,327,268.

Specification of Letters Patent.

Patented Jan. 6, 1920.

Application filed June 9, 1919. Serial No. 302,795.

To all whom it may concern:

Be it known that I, GEORGE W. CHRISTIANS, a citizen of the United States, residing at Chattanooga, in the county of Hamilton 5 and State of Tennessee, have invented certain new and useful Improvements in Methods of Sealing Crevices in Rock Formations, of which the following is a specification.

This invention relates to an improved 10 method for sealing crevices or cavities in rock or waterproofing broken or porous rock formations. It consists essentially in pumping a material, which is fluid when heated, but nearly solid and highly viscous when 15 cool, through a suitably heated pipe into the rock containing the crevices or cavities. After reaching the rock formation, the sealing material enters the crevices under pressure and then becomes cool and practically 20 solid, thus filling the crevices and effectually sealing said crevices against the passage of water and the like.

I have found from practical operations 25 that a number of different materials, such as sulfur, asphalt or coal tar pitch, may be used, but I believe that unadulterated asphalt is the best material for the process.

It has heretofore been proposed to introduce bitumen, pitch and sulfur into creviced 30 rock for the purpose of sealing the interstices but the method of introducing such materials is essentially different from my process and it has never been used to commercial advantage.

35 Cement has also been used prior to my invention for filling rock crevices and it may be of assistance at this stage to point out the advantages of my method over the cement grouting method. First, my method can be 40 successfully employed, for sealing crevices or a cave of considerable size, through which water is flowing at relatively high velocity, without loss of material by washing. In grouting, great quantities of cement 45 are often washed away and wasted before a closure is effected and then it is frequently impossible to determine whether the crevice is sealed or whether the drilled hole has become clogged. Second, a number of crevices 50 at different elevations, by my method, can be sealed equally well from the same drilled hole. I accomplish this by extending a perforated pipe through all of the crevices, so that the pressure and accessibility at each 55 equalized and when pumping has continued until a high resisting pressure has been

reached a definite assurance is obtained that all spaces adjacent to the pipe line are filled. Grouting can only be effective at one point at a time and when the introduction of the 60 cement at this point is finished, a new hole must be drilled. Third, with my method, after the work is completed at any particular hole, the pipe together with a portion of the 65 heating means are left embedded in the sealing material, so that if it is considered desirable at some future time (several years later if necessary) more material may be forced into the same hole by merely making the proper connections with the pipe and heat- 70 ing means. Then after heating for a few minutes, additional material may be introduced, the same as if the original operation had never been halted. When grouting, on the other hand, a stoppage of only a few 75 minutes allows the cement to set in the hole and consequently no more cement can be inserted. Owing to this solidifying of the cement, a new hole must be drilled if it is de- 80 sired to continue the work.

Before proceeding with a detail description of the process, it may be well to mention some practical observations had during recent successful demonstrations of my method. It has been found in practice that pitch 85 and asphalt are very poor conductors of heat and this fact very greatly assists the operation. In my process, an electrical conducting wire extends through the pipe for the purpose of maintaining the material in heat- 90 ed condition during its passage through the pipe, and the asphalt or pitch which surrounds the wire, effectually insulates the wire from the pipe, both electrically and thermally, so that while the pipe may be 95 cold yet very little heat is required to maintain a fluid passage adjacent the wire. As soon as the sealing material leaves the pipe and touches the water in the crevice, the surface of the material hardens into a tough 100 skin, but the heat conductivity is so poor, that the interior of the material remains hot and fluid. The hardened skin forms a tough 105 sack which clings to the opening in the pipe and is strong enough to resist the pressure of a considerable velocity of water or the like, but the inside of the sack and a connection between the opening in the pipe and the inside of the sack remains fluid as long as a 110 continuous flow is maintained, so that the sack can be expanded indefinitely, unless obstructed, with very little pressure. This en-

ables the introduction of the material in hot condition, so that stiff material, with a high melting point, such as unadulterated asphalt, may be successfully used.

With a view of more clearly setting forth the invention, reference may be had to the accompanying drawing, which illustrates a part of the apparatus forming the subject matter of an application filed of even date herewith and bearing Serial Number 302,796.

In the drawing:

Figure 1 is a diagrammatic view of the apparatus illustrating the manner of introducing the heated sealing material into the rock crevices under pressure.

Fig. 2 is a detail view of the material conducting pipe.

In the drawing 1 represents a supply tank or reservoir in which the hot sealing material such as pitch or asphalt is stored. A pipe 2 connects this tank with a heating chamber 3 in which the material is kept heated by means of suitable burners 4. A pump 5 is located in the heating chamber 25 and is maintained in heated condition by being submerged in the sealing material contained in the chamber 3. The pump is driven from a suitable power means (not shown) through the medium of the belt 6 and it is adapted to draw the hot material from the chamber 3 and force the same with considerable pressure into the pipe 7. The pipe 7 is provided with a suitable pressure gage 8 and located within the pipe is a heating wire 9, which is connected to an electric supply line wire 10. One end of the wire is connected by a suitable yielding device, such as a coil spring 11, to a fixed or stationary point 12, and the other end of the wire is fixed to a terminal of connector 29 which bears against an insulated plug 13, carried by one arm of a cross-shaped pipe fitting 14. The spring 11 maintains the wire 9 taut in the pipe 7. The other wire 15 of the supply line is in electrical connection with the pipe 7.

A second pipe 16 is connected to the fitting 14 and is extended down into a previously drilled hole 17, which communicates with the crevices or cracks 18 that are to be filled or sealed. The pipe 16 is made up of a number of sections 19 connected together by couplings 20 and it carries at its lower end a point 21. As will be seen from the drawing, the sections of the pipe 16, which are adjacent the crevices 18 are provided with a series of apertures 22 and located between the adjacent ends of the pipe sections 19 are insulating washers 23, which aid in maintaining an electric circuit through the pipe 16. This wire 24 is connected at its lower end 25 to the point 21 and its upper portion extends with a free fit through an insulated nipple 26 fixed to the fitting 14. The upper extremity of the wire 24 is con-

nected to the lower end of a coil spring 27, which has its upper end fixed to a stationary support 28, and this spring tends to maintain the wire 24 taut and out of electrical connection with the inner surface of the pipe 16. An electric conducting wire 29 connects the wires 9 and 24 together, so that the electric current from the line wire 10 passes through the wires 9, 29 and 24 in the order named to the point 25, then along the pipes 16 and 7 back to the line wire 15. It will be understood that the wires 9 and 24 are highly heated by the electric current and that they maintain the interiors of the pipes 7 and 16 in heated condition, so that sealing material passing through said pipes will be kept in heated condition until it passes out through the apertures in the pipe 16.

With the above described apparatus my method is carried out as follows: A suitable sealing material, which is fluid when heated but nearly solid and extremely viscous when cool, is placed in the reservoir 1. A number of different materials such as sulfur, asphalt or coal tar pitch may be employed but it is necessary that the material have a moderately low melting point, that it be an insulator of electricity, and that it be not absolutely solid and non-fluid when cooled. Unadulterated asphalt is probably the most practical material. It may be desirable to vary the consistency of the material so that when cooled it may be made more or less fluid. With asphalt, this can be done by the addition of a small percentage of crude oil. The character of the material used depends upon the conditions encountered. It is necessary that the material be stiff enough to resist any pressure tending to push it out of the crevice (such as the head water of a dam) but it must be fluid enough so that a moderate hydraulic pressure will force it the necessary distance into the crevice or crevices.

From the tank 1, the material flows through the pipe 2 into the chamber 3 where it is kept heated by the burners 4. The heated pump 5 draws the heated material from the chamber 3 and forces the same into the pipe 7 from which it is forced down the pipe 16 and out through the holes 22 into the crevices 18. During its travel through the pipes, the material will be maintained in heated condition and this is an important feature in my process, for after passing through the apertures in the pipe 16, the material acquires a thick skin, and the heated material passing from the pipe enters this skin and maintains the interior of the skin in hot fluid condition while the skin is being expanded by the pressure on the material. After the crevices are filled, the electric current is cut off and the material is permitted to cool and solidify. Then the fitting 14 is disconnected from the pipe 16.

and connected to another pipe which is used in operating on a second hole.

The operation of filling a crevice may be continuous or intermittent and as many stoppages may occur as are desirable. When shut down, the electric current is cut off and the material in the pipe line is in substantially solid condition. When starting up again, the current is turned on and in a few minutes the material in the pipe line will be heated and liquefied and ready to be pumped.

The pipe lines can be made of one inch extra heavy pipe, cut in five foot lengths with a coupling containing a lava insulating washer between each length of pipe. The pump may be located at any convenient place and the material piped for any reasonable distance to the opening of the drill hole and down the hole to the crevices. Where the pipe line passes through the crevices or porous formation, it is preferably perforated at 22 with three-quarter inch holes at three inch centers so that the material can flow out into the opening. The hot wire passing down through the pipe maintains a fluid passage so that the pressure is equalized throughout its whole length, and one material is free to expand at the points of least resistance. Where it is necessary to change the direction of the pipe line, suitable insulating fittings 14, a connector for the wires 29 and strong tension springs 11 and 27 to keep the wire taut, must be provided.

The holes down which the pipe line runs may be drilled with diamond or shot core drills or with churn type drills, and need only be two inches in diameter, and can be of any depth. For waterproofing the foundation of a dam, they should be spaced at regular intervals at such a distance that the material expanded into a crevice from one will meet the asphalt expanded from the next, and so make a complete seal. The holes may be drilled at twelve foot centers and the material pumped into them one after another.

While I have described the most essential details of my method, it will be understood that the steps of the method need not be followed in the order named. I am aware that various changes, modifications and differentiations may be made in the method without departing from the spirit of the invention as outlined in the following claims.

What I claim and desire to secure by Letters Patent is:—

1. The method of sealing crevices in fissured rock formations consisting in extending a conduit to the place where a crevice occurs, forcing a material which is fluid when heated but nearly solid when cool,

through said conduit and into said crevice, generating heat within the conduit, and utilizing the heat generated for maintaining the material in heated condition during its passage through said conduit and into said crevice. 65

2. A method of sealing a crevice under ground, which consists in drilling a hole to the place where the crevice occurs, placing a conduit having a perforated wall in said hole with the perforations adjacent said crevice, forcing a material which is fluid when heated and nearly solid when cool, through said conduit and perforations, and into said crevice, generating heat within the conduit, and utilizing the heat generated for maintaining the material in fluid and heated condition during its travel through said conduit and perforations and into said crevice. 75 80

3. A method of sealing crevices in fissured rock formations, which consists in extending a pipe provided with apertures into the rock formation and arranging the perforations adjacent said crevices, introducing a material, which is fluid when heated and nearly solid when cool, under pressure through said pipe and perforations into said crevices, generating heat within the pipe, 90 and utilizing the heat generated for maintaining the material in heated fluid condition during its travel through said pipe and perforations into said crevices. 85

4. A method of sealing a crevice in a fissured rock formation, consisting in drilling a hole through the rock to said crevice, inserting a pipe having a perforated portion into said hole and arranging the perforations of the pipe adjacent the crevice, forcing under pressure a material, which is fluid when heated and nearly solid when cool, through said pipe and perforations into said crevice, generating heat within the pipe, and utilizing the heat generated for maintaining 100 105 said material in fluid condition during its passage through the pipe and perforations into said crevice.

5. A method of sealing interstices in under ground formations, which consists in drilling a hole to the point where the interstices occur, inserting a perforated pipe into said hole and arranging the perforations of the pipe adjacent said interstices, forcing asphalt in fluid condition and under pressure through said pipe and perforations and into said interstices, generating heat within the pipe, utilizing the heat generated for maintaining the asphalt in heated condition until it is lodged in said interstices, and permitting the asphalt to cool. 110 115 120

In testimony whereof I have hereunto affixed my signature.

GEORGE W. CHRISTIANS.
